UNITED STATES PATENT OFFICE.

JOHN O. MCKEAN, OF WESTFIELD, MASSACHUSETTS, ASSIGNOR TO FOSTER MACHINE COMPANY, OF WESTFIELD, MASSACHUSETTS, A CORPORATION OF MASSACHUSETTS.

WOUND PACKAGE AND METHOD OF PRODUCING THE SAME.

Application filed November 2, 1926. Serial No. 145,854.

Tubular packages which are intended to be dyed by alternate endwise compression and expansion in the dye bath, as by the well known Franklin process, have heretofore 5 been wound of approximately the same density throughout, with the exception of the ends of the package which were necessarily wound harder because of the greater pressure due to the reversal of the winding and 10 consequent accumulation of the yarn at said ends. When these tubular packages with their softer middle portions and harder end portions were endwise compressed in the process of dyeing, the ends became still 15 harder and obstructed the thorough penetration of the dye, with the consequent result of an uneven dyeing of the package.

The object of my invention is to produce a tubular package which will be capable of 20 being evenly dyed throughout. To accomplish this object the package is wound so that it will normally be of greater density at its middle portion than at its end portions and, when compressed endwise in the dyeing 25 process, will be of substantially the same density throughout. This result is obtained by providing means for so moving the traverse guide for the yarn that the movement of the guide will be gradually increased as 30 the guide moves away from the middle portion to the limits of its travel and will be gradually decreased as the guide moves from the limits of its travel to the middle portion.

In the accompanying drawings:

Fig. 1 represents a diagrammatic side view 35 of the package in its normal state.

Fig. 2 represents a similar view with the package in its endwise compressed state.

Fig. 3 represents a diagrammatic development 40 of the traverse guide reciprocating cam.

Fig. 4 represents a detail front elevation 45 of the cam.

Fig. 5 represents a detail vertical trans- 50 verse section through the winding machine.

The tubular package is so wound that it normally has a harder middle portion 1 and 55 softer end portions 2, 3.

The usual package holder is denoted by 4, 50 the winding drum by 5 and the traverse guide by 6.

The movement of the traverse guide 6 is 55 gradually increased as the guide is moved from the middle portion to the limits of its travel and gradually decreased as the guide

is moved from the limits to the middle portion of its travel, so that the package will be wound with a greater density at its middle portion than at its ends.

In the present instance this variable movement of the traverse guide 6 is accomplished by so shaping the groove 7 of the guide reciprocating cam 8 that it will have gradually increased pitches from its center toward both ends, thereby causing the traverse 65 guide to move faster at both extremities of its traverse and slower at its mid-traverse position.

The wound package will thus normally have a greater density at its middle portion 70 than at its ends so that when the package is compressed endwise as in the process of dyeing, it will be of substantially the same density throughout.

In the development of the cam groove 75 shown in Fig. 3, the lines A, A, A, indicate the usual pitch of the cam groove for an even winding of the tubular package while the curved lines B, B, B, indicate one example of the variable pitches of the cam groove 80 from its mid-portion to its ends, whereby the uneven winding of the package is accomplished with the ends softer than the middle thereof.

I have found that a package wound as 85 above described will, when subjected to the alternate endwise compression and expansion in the die bath, evenly and rapidly absorb the dye, thereby ensuring a better product in a lesser time than has been possible 90 heretofore.

What I claim is:—

1. A cylindrical tubular package of substantially the same diameter from end to end and of greater density at its middle portion than at its end portions. 95

2. A cylindrical tubular package of substantially the same diameter from end to end and of greater density at its middle portion than at its end portions, said package being 100 compressible endwise into substantially the same density throughout.

3. A cylindrical tubular package of substantially the same diameter from end to end and having a harder middle portion and 105 softer end portions.

4. A cylindrical tubular package of substantially the same diameter from end to end and having a harder middle portion and softer end portions, said package being com- 110

pressible endwise into substantially the same hardness throughout.

5. A cylindrical tubular package of substantially the same diameter from end to end and of greatest density at its middle portion and gradually decreasing in density to its ends.

10 6. A cylindrical tubular package of substantially the same diameter from end to end and of greatest density at its middle portion and gradually decreasing in density to its ends, said package being compressible endwise into substantially the same density throughout.

15 7. A cylindrical tubular package of sub-

stantially the same diameter from end to end and of greatest density at its middle portion and uniformly decreasing in density to its ends.

8. A cylindrical tubular package of substantially the same diameter from end to end and of greatest density at its middle portion and uniformly decreasing in density to its ends, said package being compressible endwise into substantially the same density 20 throughout.

In testimony, that I claim the foregoing as my invention, I have signed my name this 28th day of October, 1926.

JOHN O. McKEAN.
